UNITED STATES PATENT OFFICE

ANDREW R. RIDDERSTROM, OF NAHANT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

FOLDING MACHINE AND METHOD

Application filed September 1, 1920, Serial No. 407,336. Renewed May 28, 1928.

The present invention relates to folding methods and machines, and more particularly to methods of and machines for folding a binding strip around the edge of a boot or shoe upper to which it is attached. The more important features of novelty of the present invention are claimed in Letters Patent No. 1,527,396, February 24, 1925. The claims of the present application are restricted to subsidiary features of novelty, many of which are of broader application than to folding machines.

The binding strip is usually sewed upon a face of the upper along an edge thereof, after which the strip is folded around the said edge and into even contact with the opposite face. In order that the binding strip, after folding, may lie evenly and smoothly against the said opposite face, it is necessary that the strip be first wiped tightly across the edge to which it is secured and then pulled and held tightly during the folding operation and while it is pressed against the said opposite face; and it is necessary also that the strip be folded exactly at the proper points or lines, and not to one side thereof.

It is an object of the present invention to provide an improved method of and machine for folding binding strips. With this and other objects in view, the invention consists of the method and machine an embodiment of which is hereinafter described, illustrated in the accompanying drawings and defined in the appended claims.

In the drawings, Fig. 1 is an elevation, partly in longitudinal section, upon a reduced scale, of a machine embodying the present invention; Fig. 2 is a plan of the forward part of the machine; Fig. 3 is an elevation of the forward part of the machine, showing parts broken away and in section; Fig. 4 is a perspective of a rotary wiper and a co-operating retainer, with connected elements, and showing also an adjusting handle in position; Fig. 5 is a longitudinal section of the rotary wiper; Fig. 6 is a longitudinal vertical section taken substantially upon the line 6—6 of Fig. 2, looking in the direction of the arrows; Fig. 7 is a front view of the upper forward part of the machine, showing the stock-sup-

porting table in section along the line 7—7 of Fig. 1, looking in the direction of the arrows; Fig. 8 is a transverse vertical section taken substantially upon the line 8—8 of Fig. 2, looking in the direction of the arrows; Figs. 9 and 10 are enlarged detail plans showing two steps performed in the illustrative machine during the operation of folding a binding strip attached to a shoe upper; Fig. 11 is an elevation corresponding to the plan of Fig. 9, with the shoe upper and the binding strip in section; Fig. 12 is an elevation corresponding to the plan of Fig. 10, showing the upper and the binding strip in vertical section along the line 12—12 of Fig. 10, looking in the direction of the arrows; Figs. 13 and 14 are views similar to Figs. 9 and 10, showing two additional steps in the operation of the illustrative machine; Fig. 15 is an elevation corresponding to the plan of Fig. 13, showing the upper and the binding strip in vertical section along the line 15—15 of Fig. 13, looking in the direction of the arrows; Fig. 16 is a vertical section taken upon the line 16—16 of Fig. 14, looking in the direction of the arrows; Fig. 17 is a section of a shoe upper, showing an unfolded binding strip attached thereto; Fig. 18 is a section similar to Fig. 17, showing the binding strip in finally folded position upon the upper; Fig. 19 is a front view showing a modified form of wiper constituting the subject matter of a copending application, Serial No. 581,154, filed August 11, 1922; Fig. 20 is a corresponding view of the rotary wiper; and Figs. 21 and 22 are views corresponding to Figs. 19 and 20, respectively, illustrating the wiping action.

The invention is illustrated in the accompanying drawings in connection with the folding of a binding strip 2 of cloth, silk and the like, around the edge 4 of a sheet of leather or other material 6, such as a boot or shoe upper. An edge 8 of the binding strip is stitched at 12 to a face 10 of the shoe upper along the edge 4, so that the sheet and the strip extend at an angle to each other from the secured-together edges 4 and 8. It will be understood that the invention is equally applicable to other articles than that which

is herein chosen for purposes of illustration, and the elements of the article need not necessarily be of the relative dimensions shown.

The shoe upper is initially placed in the machine upon a platform or support 24, Figs. 6, 10 and 12, with the face 10 of the upper in contact with the support. An end of the free or unsecured edge 26 of the strip 2 is initially moved across and around the secured-together edges 4 and 8, and into the space between an interior side face 28 of a feed point 30 and a plow 32 that stands up integrally from a plate 34. The plate 34 is mounted upon a folder 93 that is secured, as by a set screw 95, to a support 94 that rocks about a rod 96. The rod 96 is secured to the frame of the machine by a screw 98. The machine being set into operation, successive portions of the unsecured edge or portion of the strip 2 near the stitches 12 are intermittently wiped tightly across the secured-together edges 4 and 8, or away from the stitches, as shown more particularly at 36, Fig. 15, by the combined action of a wiper 38 and a retainer point 40 that presses down heavily at this time upon the upper directly opposite to the point of action of the wiper. It is very important to the subsequent operation that the strip be wiped very tightly. In order to enable the wiper 38 to operate, the strip 2 is progressively moved lightly or loosely by the operator's fingers from the position of Fig. 17 more or less into the plane of the shoe-upper sheet 6, as the shoe upper is fed forward through the machine. The successively wiped portions are initially intermittently folded around the secured-together edges 4 and 8 by the plow and they are gripped intermittently between the interior side face 28 of the feed point and the plow 32, becoming thereby pulled tightly. The intermittent wiping, and folding and gripping operations are performed upon the successive portions of the strip alternately during successive pauses in the feed. The plow-folded portions are advanced by the feed point and a cooperating feed block 41 that is carried integrally with the plow 32 upon the plate 34 to a combined folder and fold presser 42. The fold presser folds the plow-folded portions of the strip further and presses them down against the other face 16 of the sheet, as shown in Fig. 18. The preferred fold presser 42 is described in the said Letters Patent, and in Letters Patent No. 1,527,395, also granted February 24, 1925.

These operations are continued in timed relation to one another until the whole strip has become folded, as described more fully in the said Letters Patent No. 1,527,396. Reference is made to the said Letters Patent for a fuller description of so much of the machine as is not fully disclosed herein, because unnecessary to an understanding of the present invention.

The wiper 38 of the present invention comprises, in its illustrated form, a rotary disk centrally hollowed out at 44, so as to present a raised ridge 46 along its upper circumference. The hollowed-out structure is unimportant, except in that the raised ridge is thereby provided for. The ridge is preferably milled or roughened, as shown. The wiper is rotated in the direction of the curved arrow, Fig. 9. To this end, the underside of the wiper disk is provided with teeth 48, Figs. 4 and 5, meshing with worm threads 50 upon one end of a shaft 52 mounted in a bearing 54, Fig. 2. The other or free end of the shaft 52 is provided with a ball 56 mounted in a socket 58 upon the forward end of a shaft 60. The purpose of this construction is primarily to permit of adjusting the wiper vertically. This may be effected by vertically adjusting a bracket 61, Fig. 3, that carries the bearing 54, through the medium of screws 63 in enlarged openings 65 of the bracket. The vertical adjustment may be effected without disturbing the ball-and-socket connection between the shafts 52 and 60, as described in the said Letters Patent No. 1,527,396.

The shaft 60 carries a gear 62 that meshes with a gear 64 upon a driving shaft 66 that is horizontally journaled in bearings of the machine frame. The ball-and-socket connection permits the shaft 60 being inclined to the driving shaft 66. By means of this construction, the wiper is rotated from the driving shaft through the medium of a pin-and-slot relationship between the ball and the socket elements of the ball-and-socket connection. The driving shaft 66 is driven by mechanism shown more particularly in Fig. 1, and need not be further described, as a full description may be found in the above-mentioned Letters Patent. The said Letters Patent contain also a description of the details of the construction and operation of the feed mechanism.

The feed point 30 is pivotally mounted at 110 upon the rocking support 94 so as to be rocked or oscillated therewith and with the lower feed block 41, as described in the said Letters Patent, and is normally maintained in contact with the feed block by a leaf spring 112. The body portion 118 of the feed point is slotted and a screw post 120 is adjustably clamped between the side walls of the slot by a screw 122, Fig. 6. The upper face 104 of a diagonally cylindrical block 102 is adapted to engage the post 120, thereby to raise the feed point 30, in opposition to the pressure of the spring 112. The degree of adjustment of the screw post 120 determines the amount by which the feed point will be raised above the feed block. The screw 122 may also be employed to take up for wear. An additional adjustable member 123 is provided to prevent the feed point, which is preferably provided with gripping teeth, becoming lowered into

contact with the feed block when the machine is running idly, thereby preventing the feed point pounding uselessly against the feed block when no stock is interposed. In the absence of the member 123, the screw post 120 5 may be suitably adjusted for a similar purpose. The tension of the spring 112 upon the body portion 118 of the feed point may be adjusted by a clamp screw 124, Figs. 1 and 9, 10 having a shoulder 126 for engaging the spring. The feed point may thus be caused to engage the stock with varying degrees of 15 pressure dependent upon the degree of adjustment of the clamp screw 124. In order to prevent lateral movement of the spring 112, it is mounted in a longitudinal slot 128 provided in the upper surface of the machine frame.

During the left-to-right oscillating movement of the rocking support 94, as described 20 in the aforesaid Letters Patent No. 1,527,396, the separated feed point and feed block move backward from the fold presser towards the wiper. The feed elements are thus returned 25 to take a new hold upon the stock, in preparation for the next forward movement of the feed elements. Portions of the strip 2 that have previously been wiped are during this return movement engaged by the plow and by 30 it given an initial fold, as will be clear from Fig. 9. In this figure, the feed elements and the plow are shown as having retracted their movement to the starting point and as about to move forward again, in the direction of the 35 arrow. As the plow is integral with the feed block, it will oscillate with the feeding means. The mounting of the plow and, therefore, also of the feed block, is pivotal for purposes of adjustment, the pivot point being shown at 40 130, Figs. 6 and 16, but a stiff coil spring 132, mounted in a recess 134 of the plate 34, and acting against the body of the plate 34 at 136, and against the holder 93 at 137, renders the plow practically rigid with the rocking support, except that provision is thereby made 45 for clearing seams and other irregularly thick parts of the strip without injuring the same. In case the plow wears down, or if it is desired, for other reasons, to adjust the plow 50 relatively to the feed point 30, as when it is desired to operate upon thicker or thinner strips, the adjustment may be effected along the active face of the plow by means of an adjusting screw 138 threaded in a lug 140 of the 55 plate 34 and engaging the rocking support 94 at 142.

The space between the feed point and the plow should be just large enough to enable the plow to fold most effectively, without 60 interference from friction by the feed point, and neither larger nor smaller. The desired relation between the feed point and the plow may be regulated to some extent by the adjusting screw 138. When the feed point and 65 the plow are properly positioned relatively

to each other, the feed point, during its descent, will approach the plow at an angle, from the dotted-line position to the full-line position of Fig. 6, to force the strip tightly inward against the plow and to maintain the 70 strip pulled tight during the subsequent feed movement until the feed point again rises preparatory to the next return feed movement. When the feed point rises, the strip is readily released once more, so that it again 75 lies loosely, enabling the plow to fold properly.

As described in the above-designed Letters Patent Nos. 1,527,395 and 1,527,396, the fold presser is floatingly pivoted at 146, Fig. 80 3, to one end of a link 148 the other end of which is eccentrically connected by a pin 150, Fig. 1, to a spiral gear 152 meshing with a spiral gear 154 upon the driving shaft 66. The exterior surface of the fold presser is 85 cylindrical, as shown at 156, Figs. 3 and 12, so as to rock within a cylindrical bearing 158 provided at the free end of an arm 160 the other end of which is pivoted at 162.

Sometimes, it is desired to have the stock 90 rest upon a table 176, shown in Fig. 1 as supported by adjustable abutments 178, and encircling the platform or support 24 and the operating mechanism. Upon other occasions, this table may be pivotally moved out of the 95 way about a pivotal axis 179. The table is of relatively small width at the side next to the operator, as will be clear from Fig. 7, so that the stock may be fed to the operating instrumentalities without the table causing the strip 100 that is underneath the upper to resist by friction the wiping action of the wiper. On the other side, the table may be of relatively large width to permit the stock resting 105 thereon.

The retainer of the present invention may assume any one of a number of forms. It is illustrated in most of the views as comprising not only the retainer 153, which corresponds, in some degree, to the retainer of the above-described Letters Patent No. 1,527,395, but the retainer point 40 as well, the latter co-operating with the wiper. The retainer-operating mechanism will be described first and is claimed herein. Claims not limited to the specific retainer or its operating mechanism may be found in the aforesaid Letters Patent No. 1,527,396.

A pin 180, Fig. 4, is transversely fixedly 110 secured to the rear end of a rock shaft 182 and forms the ball element of a ball-and-socket connection the socket element 184 of which is provided at one end of a link 186. The shaft 182 is rockingly mounted in bearings of the machine frame. The other end of the link is similarly connected by a ball-and-socket connection 188 to a bell-crank lever 190 that is pivoted to the frame of the machine at 192. The lever is connected at 194 by a link 196 to the same pin 150 by which 120 125 130

the link 148 is eccentrically connected to the gear 152, Fig. 1. The retainer 153, Fig. 4, is thus operated in timed relation to the wiping, feeding and folding instrumentalities through the gear 154, Fig. 1, that is mounted upon the driving shaft 66. By suitably designing the relative positions of the points 150, 192 and 194, a little better timing of the fold presser and the retainer 153 is rendered possible than in the machine of the previously-mentioned Letters Patent No. 1,527,395. As the gear 152 is rotated through a complete revolution to effect the operation of the fold presser, through the pin 150 and the link 148, the bell-crank lever 190 will cause the link 186 to rock about the pins 180 and 188 towards the left, as viewed in Fig. 4, to and beyond the dead-center point, and back to its original position. As the pivotal point 192 is fixed in position upon the machine frame, the link 186 will be carried upwards during its rocking movement, causing the pin 180 to rock the shaft 182. The shaft 182 will be rocked to its limiting position when the link 186 reaches the dead-center point, but owing to the below-described, resilient mounting of the retainer upon the shaft 182, the retainer 153 will operate to press down upon the stock, and the retainer point 40 will press the stock against the wiper, for a period of time preceding and following the attainment of the dead-center point by the link 186. The retainer and the retainer point are in this manner caused to dwell for a relatively longer period of time. During this period, the fold presser operates to press the strip against the upper, the feed point thereupon rises to release the work, and the fold presser and the feed elements return to their initial positions. At the end of the return movement, when the feed elements close in upon the stock, to feed it forward again, the link 186 moves so as to release the retainer, so that the feeding movement may commence again without interference from the latter.

The retainer and the retainer point are resiliently mounted upon the shaft 182 in a new and improved manner, shown more particularly in Figs. 2, 4 and 8. A reduced shaft 198, which may be termed the retainer shaft, is loosely mounted in a hollow, forward portion 200 of the shaft 182. This loose mounting is functionally of value; for if either of the shafts 182 and 198 were snugly mounted in an unyielding, axial bearing of the other, the retainer and the retainer point mounted at the end of the retainer shaft 198 could not yield properly to press down upon the stock with evenly applied, equally divided tension, as is desirable. The friction of one shaft upon the other would prevent the attainment of this result, which is possible with the loose mounting illustrated. A hub 202 integrally connects the hollow portion 200 to the body portion of the shaft 182. The hub 202 is pro-

vided with a transverse recess 204 within which is received a lug 206 that is secured to the reduced shaft 198, as by means of a set screw 208. A coil spring 216 maintains the lug 206 in engagement with the hub 202, so that the rocking movement of the shaft 182 may be yieldingly communicated to the retainer shaft 198. In order that the engagement of the lug 206 with the hub 202 may be adjustable, a screw 210 is adjustably mounted in the lug 206. To permit adjusting the screw 210 without removing the removable housing 212, an opening 214 is provided in the housing through which a suitable tool may enter.

The coil spring 216 that maintains the screw 210 in engagement with the hub 202 is fastened at one end 217 to the lug 206, and at the other end 218 to a clutch element 220 that is loosely mounted about the shaft 182. The clutch element is adapted to co-operate with a clutch element 222 that is fixed to the shaft 182, as by means of a set screw 224. The clutch elements 220 and 222 are shown provided with inter-engaging, one-way, ratchet teeth 226. To adjust the tension of the spring 216, the clutch element 220 may be rotatably adjusted about the shaft 182. To this end, the clutch element 220 is provided with a plurality of openings 228 adapted to receive an adjusting handle 230. The handle 230 may be inserted through an opening 331, Fig. 2, of the housing 212. Actuation of the handle in one or the other direction, together with a slight sidewise movement, if actuated counter-clockwise, will rotatably adjust the position of the clutch element 220 relatively to the clutch element 222. The ratchet teeth 226 prevent accidental rotation of the clutch element 220 in a direction opposed to the force of the coil spring. The tension of the spring may, in this manner, through the retainer point 40, be made to yield a wiping action by the wiper upon the strip 2 of any desired degree of tightness. The tension may be made so great, indeed, as to cause the wiper to tear the strip entirely away from the upper. In practice, the strip should be wiped just tightly enough to show the stitches at the seam joint between the upper and the strip, at 233, Fig. 21. If properly adjusted, the retainer will permit the wiper to act with the desired degree of tightness without the teeth 232 of the retainer point scratching the stock.

The retainer 153 and the retainer point 40 are carried upon a support 236 that is pivoted at 238 to the curved end 239 of the reduced retainer shaft 198. A spring 240 engages under a projection 242 of the support 236 and presses yieldingly against the projection to maintain the latter in engagement with an adjustable limiting stop 244, mounted upon the retainer shaft 198. This yielding, pivotal mounting of the retainer 153 and of the retainer point 40 helps to provide for equally

distributed tension upon the stock by the retainer and the retainer point independently of variations in the thickness of the stock. The stop 244 is shown in the form of a screw, which may be threaded in or out a distance sufficient to prevent the teeth 232 of the retainer point striking against and injuring the wiper when the machine runs idly.

As in the above-referred-to Patent No. 1,527,395, the chief purpose of the retainer 153 is to prevent the stock being pushed outward away from the operating instrumentalities of the machine and to hold the stock firmly against accidental movement during the return movement of the feed elements. It is found, in practice, however, that the retainer point 40 is capable of performing these functions, in addition to the function for which it is primarily designed. This is particularly true when the retainer point 40 is supplied with the teeth 232 and is properly tensioned by the coil spring 216. The retainer 153 may therefore be dispensed with and the retainer point 246 may be directly connected to the retainer shaft 198, as is disclosed in the above-named Letters Patent No. 1,527,396. A still simpler construction, in which the retainer 253 acts continuously against the stock, is illustrated in Fig. 1 of the said copending application, Serial No. 581,154, filed August 11, 1922.

A retainer of this simpler character is particularly adapted for use with a stationary wiper of the type shown in Figs. 22 and 24 and in said application, Serial No. 581,154, though it may also be employed with the rotary wiper. This is because the wiping action of the modified wiper is entirely due to dragging the stock over the wiper, whereas when the rotary wiper is employed, the wiping action is caused primarily by the rotation of the wiper and secondarily by dragging the stock thereover at a time when the retainer point presses down less heavily, if at all. This will be discussed in further detail below. When the modified wiper is employed, therefore, it is well to have a retainer that presses down upon the stock during the dragging action. It will be understood, in this connection, that the screw 210 may be adjusted so that the retainer point never becomes completely raised from the work, but so that it is always effective to exert some pressure, though this pressure may be very slight during the stock-feeding movement.

In order to insert the stock, it is necessary to raise the retainer and the retainer point with the feed point. To effect this, an arm 318 is secured to the shaft 198 so as to extend above the feed point and to be engaged thereby when the feed point is raised by the treadle (not shown). As the feed point becomes raised, therefore, the shaft 198, with the retainer and the retainer point carried thereby, will be rocked axially, separating the

screw 210 from the hub 202, in opposition to the action of the coil spring 216, the retainer and the retainer point becoming thus raised. The arm 318 is provided with a finger piece 320 to permit raising the retainer and the retainer point manually independently of the feed point.

The operation of the modified form of wiper shown in Fig. 19 is illustrated in Fig. 21 and is described in the said application Serial No. 581,154. Views of the preferred rotary wiper and its operation corresponding to Figs. 19 and 21 are shown in Figs. 20 and 22. The modified wiper comprises a raised diagonally outstanding finger or bar 321 that is rigidly secured to the frame of the machine, as by a screw at 322. As the stock is advanced in the direction of the arrow, the strip 2 rides over the finger or bar 321, becoming wiped thereby. The action is substantially the same as that of the rotary wiper while the stock is being fed forward, the diagonal finger or bar being raised similarly to the raised circumferential edge 46 of the rotary wiper. Were the rotary wiper stationary, the action of the raised edge, like that of the finger or bar 321, would be the whole action of the wiper. The rotation of the rotary wiper effects the additional result of positively rubbing or dragging or stretching outward at isolated points of the strip, while the strip is stationary during the return feed movement, to wipe the strip tightly across the edge of the sheet. The stationary wiper 321 can not perform this additional function.

The operation according to the present invention will be better understood from a study of Figures 9 to 16, which represent the relative positions of the operating instrumentalities of the illustrative machine at four equally spaced points in the cycle of operation. In Figs. 13 and 15, the feed elements are assumed to have reached the end of their forward movement. During this forward movement, the retainer and the wiper have both released their hold upon the stock. The fold presser is assumed to be descending to iron out the fold.

During the fold-pressing operation, the feed point rises, as is shown more particularly in Fig. 17, releasing its hold upon the material. With the feed block and the plow, it then returns towards the positions illustrated in Figs. 9 and 11. During this return movement, the retainer 153 and the retainer point 40 press down hard, the latter pressing against the stock at a point opposite to the point of operation of the wiper. The wiper thus co-operates with the retainer point at this time, while the strip is stationary, to wipe or stretch the strip tightly across the edge of the stock, as shown in Fig. 15. The rotating, circumferential raised edge 46 of the wiper engages successive isolated points of the binding strip, wiping

the strip at these points tightly across the secured-together edges 4 and 8, Fig. 17, towards the right, in Figs. 9 to 16, just a little below the plane of the upper, as shown more particularly at 36 in Fig. 15. During the return movement of the feed elements, the plow initially folds that portion of the strip over which it rides and which has been previously wiped, as will be clear from the successive positions shown in Figs. 13, 14 and 9. The plow may be inclined at the most suitable angle, as shown in Fig. 6, for performing this folding operation most effectively. As the plow is rigid with the feed block, it acts also as a gage. The wiper is effective during substantially the whole return movement of the plow, and the folding operation of the plow continues until the plow is returned to a point very close to the wiper, as shown in Fig. 9. Towards the end of the return movement of the feed elements, the feed point descends obliquely to the plow, from the dotted-line position to the full-line position of Fig. 6, effecting frictional engagement of the strip between the plow and the interior side face 28 of the feed point, and causing the wiped strip to be pulled tightly in a direction away from the stitches. The feed point and the feed block clamp the material in preparation for the next forward feed movement, Figs. 9 and 11. The feed point and the plow maintain their tight hold upon the strip during the forward movement of the feed elements until the feed point again rises, at the end of the said forward movement. As the feed point, the feed block and the plow move forward, they drag the stock over the wiper. As the raised circumferential edge 46 is higher than the body of the wiper, as will be clear from Fig. 22, this dragging action helps to wipe portions of the strip not previously wiped by the rotary action of the wiper. As has been explained before, the rotary wiper acts at isolated points only, while the stock is stationary, during pauses in the feed, the points intermediate these isolated points being wiped by the above-described dragging action during the forward movement of the feed elements. The stock is solidly gripped at all times during the forward movement of the feed elements, permitting no opportunity for the stock to slip, and the line of fold of the strip about the edges 4 and 8 is absolutely predetermined. The initial, predetermined fold is advanced under the fold presser, by which it is further folded and pressed. The above-described cycle of operations is then repeated.

Changes and modifications will obviously occur to persons skilled in the art, and these are considered to be embraced within the spirit and scope of the present invention, as defined in the appended claims.

The invention having been thus illustrated and described what is claimed as new is:—

1. A machine for folding a strip around the edge of a sheet of material to one face of which, along the said edge, an edge of the strip is secured so that the sheet and the strip extend from the secured-together edges at an angle to each other, the said machine having, in combination, a wiper adapted to rotate in substantially a plane parallel to the plane of the sheet for wiping successive portions of the strip across the secured-together edges, means for rotating the wiper, means for folding the successively wiped portions of the strip around the secured-together edges, and means for pressing the successively folded portions of the strip into contact with the other face of the sheet.

2. A machine for folding a strip around the edge of a sheet of material to one face of which, along the said edge, an edge of the strip is secured so that the sheet and the strip extend from the secured-together edges at an angle to each other, the said machine having, in combination, a wiper adapted to rotate in substantially a plane parallel to the plane of the sheet for wiping successive portions of the strip across the secured-together edges, means for rotating the wiper, a retainer adapted to press upon the other face of the sheet at a point opposite to the point of action of the wiper during the wiping action of the wiper, means for folding the successively wiped portions of the strip around the secured-together edges, and means for pressing the successively folded portions of the strip into contact with the other face of the sheet.

3. A machine for folding a strip around the edge of a sheet of material to one face of which, along the said edge, an edge of the strip is secured so that the sheet and the strip extend from the secured-together edges at an angle to each other, the said machine having, in combination, a wiper for wiping successive portions of the strip across the secured-together edges, a shaft for actuating the wiper, a bracket upon which the shaft is carried, means for adjusting the bracket, means for determining the position of adjustment of the bracket, a shaft for driving the actuating shaft universally connected to the actuating shaft, means for driving the second-named shaft, means for folding the successively wiped portions of the strip around the secured-together edges, and means for pressing the successively folded portions of the strip into contact with the other face of the sheet.

4. A machine of the class described having, in combination, a wiper for wiping a strip across the edge of a sheet of material to one face of which, along the said edge, an edge of the strip is secured so that the sheet and the strip extend from the secured-together edges at an angle to each other, a shaft for actuating the wiper, a shaft having a ball-

- and-socket connection with the actuating shaft, and means for driving the second-named shaft, the ball and the socket elements of the ball-and-socket connection having a pin-and-slot relation to permit the second-named shaft to drive the actuating shaft. 5
5. A machine for folding a strip around the edge of a sheet of material to one face of which, along the said edge, the strip is secured, the said machine having, in combination, means for feeding the sheet and the strip, the said means comprising a feed element that is constructed and arranged to engage the strip to fold the strip around the said edge and to engage the said edge through the strip to gage the sheet, and means for operating the feed means. 10
6. A method of folding a strip around the edge of a sheet of material to one face of which, along the said edge, the strip is secured, the said method comprising engaging the said edge with a member through the strip to fold the strip around the said edge and gage the sheet, and advancing the sheet and the member to feed the sheet and the strip. 15
7. A folding machine having, in combination, a feed element having an interior side face, a plow between which and the side face material is adapted to be gripped, the plow having an active face extending at an angle to the direction of feed, and means for relatively adjusting the plow and the feed element along the line of extension of the active face of the plow at the said angle to the direction of feed. 20
8. A folding machine having, in combination, a feed block, a plow, a feed point having a portion between which and the plow material is adapted to be gripped, the feed block and the feed point being constructed and arranged to feed material, the plow having an active face extending at right angles to the direction of feed, and means for pivotally adjusting the plow to move towards and from said feed-point portion along the line of extension of the plow at right angles to the direction of feed. 25
9. A machine of the class described having, in combination, a feed element, a retainer, and means whereby the feed element is adapted to engage the retainer to cause the retainer to be actuated with the feed element when the latter is actuated in a predetermined direction. 30
10. A machine of the class described having, in combination, a wiper for wiping a strip across the edge of a sheet of material to one face of which, along the said edge, the strip is secured, an adjustable retainer support, and a retainer for retaining the sheet against movement adjustably mounted upon the retainer support and adapted to co-operate with the wiper. 35
11. A machine of the class described hav- 40
- ing, in combination, a wiper for wiping a strip across the edge of a sheet of material to one face of which, along the said edge, the strip is secured, a retainer support, and a spring-pressed retainer for retaining material against movement adapted to cooperate with the wiper, the retainer being mounted on the support to pivot in opposition to the force of the spring. 45
12. A machine of the class described having, in combination, a retainer shaft, and a retainer support mounted on the shaft having a retainer and a retainer point, the retainer point being yieldingly connected to the shaft. 50
13. A machine of the class described having, in combination, a hollow rock shaft, a shaft loosely mounted therein carrying a retainer, and a spring connection between the shafts. 55
14. A machine of the class described having, in combination, a shaft, a retainer mounted loosely thereon, means for adjusting the normal angular position of the retainer upon the shaft, and a coil spring connecting the shaft to the adjusting means. 60
15. A machine of the class described having, in combination, a shaft, a retainer loosely mounted thereon, a coil spring connecting the retainer and the shaft, and means for adjusting the tension of the spring. 65
16. A folding machine having, in combination, a wiper, a retainer co-operating therewith, and means for rendering the retainer alternately heavily and less heavily effective. 70
17. A machine of the class described having, in combination, a horizontally rocking support having a vertically disposed opening, a feed element mounted on the support over the opening, a rod slidably mounted in the opening, a rod loosely connected to the support upon which the slidably mounted rod rests, a lever upon which the loosely connected rod rests, and manually controlled means for actuating the lever to cause the raising of the feed element. 75
18. A machine for folding a strip around the edge of a sheet of material to one face of which, along the said edge, an edge of the strip is secured so that the sheet and the strip extend from the secured-together edges at an angle to each other, the said machine having, in combination, means for moving the strip across the secured-together edges, means for folding the moved strip, and a table encircling the moving and folding means of relatively small width at one side of the moving and folding means and relatively large width at the other side of the moving and folding means, whereby the sheet of material may be fed with the strip underneath from the one side without hindrance from the table and may be supported by the table at the other side of the folding means. 80
19. A folding machine having, in combination, a plow having an upstanding, active 85

face, a feed point having a face adapted to co-operate with the active face of the plow, means for actuating the feed point to cause its active face to approach obliquely the active face of the plow, and means for relatively adjusting the plow and the feed point along the upstanding active face of the plow.

20. A machine of the class described having, in combination, a wiper, a retainer shaft, a retainer mounted thereon, a shaft spring connected to the retainer shaft, means for adjusting the tension of the spring-connection, and means for adjusting the retainer upon the retainer shaft.

21. A machine of the class described having, in combination, a wiper, a retainer shaft, a retainer for clamping material against the wiper mounted on the shaft, and means for adjusting the retainer upon the shaft to prevent the retainer coming into contact with the wiper.

22. A method of folding a strip around the edge of a sheet of material to one face of which, along the said edge, the strip is secured, along the said edge, the strip is set the strip around the said edge, engaging the said edge with a member through the strip to gage the sheet, and feeding the sheet and the strip.

23. A machine for folding a strip around the edge of a sheet of material to one face of which, along the said edge, the strip is secured, the said machine having, in combination, means for feeding the sheet and the strip and for folding the strip around the said edge, and a member engaging the said edge through the strip to gage the sheet.

24. A machine for folding a strip around the edge of a sheet of material to one face of which, along the said edge, the strip is secured, the said machine having, in combination, means for feeding the sheet and the strip, and means for engaging the said edge through the strip to gage the sheet, pulling the strip tightly and folding it around the secured-together edges, and pressing the strip into contact with the other face of the sheet, the last-named means comprising a combined gage and strip-pulling member.

25. A folding machine having, in combination, a support upon which material is adapted to rest, a plow for initiating a fold in the margin of the material pivoted to the support so as to move pivotally in a plane at right angles to the support, and means yieldingly maintaining the plow in a limiting position of pivotal movement.

26. A folding machine having, in combination, a support upon which material is adapted to rest, a plow for initiating a fold in the margin of the material pivoted to the support so as to move pivotally in a plane at right angles to the support, and means mounted upon the support for yieldingly maintain-

ing the plow in a limiting position of pivotal movement.

27. A machine of the class described having, in combination, a feed block, a feed point, means for reciprocating the feed block and the feed point, means for moving the feed point toward the feed block during the movement of the feed point and the feed block in one direction of reciprocation, and means for adjustably limiting the degree of movement of the feed point toward the feed block.

28. A machine of the class described having, in combination, a feed block, a feed point, means for reciprocating the feed block and the feed point, means for moving the feed point toward the feed block during the movement of the feed point and the feed block in one direction of reciprocation, and two means, each adapted separately to limit the degree of movement of the feed point toward the feed block.

29. A machine of the class described having, in combination, a feed block, a feed point, means for reciprocating the feed block and the feed point, means for yieldingly moving the feed point toward the feed block during the movement of the feed point and the feed block in one direction of reciprocation, means for adjusting the yielding action of the yielding moving means, and means for limiting the degree of movement of the feed point toward the feed block.

30. A machine of the class described having, in combination, a feed block, a feed point, means for reciprocating the feed block and the feed point, a leaf spring for moving the feed point toward the feed block during the movement of the feed point and the feed block in one direction of reciprocation, and a member having a slot in which the leaf spring is mounted to prevent lateral movement of the leaf spring.

31. A folding machine having, in combination, means for feeding material, a pivoted plow for folding the material, means for maintaining the plow yieldingly in a predetermined position, and means for adjusting the predetermined position, the yielding-maintaining means being stiff so as to render it practically unyielding except under predetermined conditions.

32. A folding machine having, in combination, oscillating means, a plow mounted upon the oscillating means so as to oscillate therewith, means for maintaining the plow yieldingly in a predetermined position, and means for adjusting the predetermined position, the yielding-maintaining means being stiff so as to render it practically unyielding except under predetermined conditions.

In testimony whereof, I have hereunto subscribed my name this 30th day of August, 1920.

ANDREW R. RIDDERSTROM.

130

CERTIFICATE OF CORRECTION.

Patent No. 1,740,408.

Granted December 17, 1929, to

ANDREW R. RIDDERSTROM.

It is hereby certified that error appears in the printed specification of the above numbered patent requiring correction as follows: Page 3, line 32, for the word "retracted" read "retraced"; page 8, line 25, claim 22, strike out the words and syllable "along the said edge, the strip is se-" and insert instead "the said method comprising folding"; and that the said Letters Patent should be read with these corrections therein that the same may conform to the record of the case in the Patent Office.

Signed and sealed this 20th day of May, A. D. 1930.

(Seal)

**M. J. Moore,
Acting Commissioner of Patents.**
